UNITED STATES PATENT OFFICE.

LEWIS BAILEY SKINNER, OF DENVER, COLORADO.

FEEDING APPARATUS.

1,375,643.

Specification of Letters Patent. Patented Apr. 19, 1921.

Application filed February 19, 1920. Serial No. 359,956.

To all whom it may concern:

Be it known that I, LEWIS B. SKINNER, a citizen of the United States, residing at Denver, in the county of Denver and State 5 of Colorado, have invented certain new and useful Improvements in Feeding Apparatus; and I do hereby declare the following to be a full, clear, and exact description of the invention, such as will enable others 10 skilled in the art to which it appertains to make and use the same.

This invention relates to feeding apparatus and more particularly to apparatus that is adapted for feeding acids or other 15 corrosive materials in regulable quantities from a source of supply to a place of use. One of the most important practical applications of the invention is in feeding sulfuric acid to a muriatic acid and salt cake 20 furnace; and for the sake of a concrete illustrative example, an acid feeder embodying the principles of the invention and especially adapted for use with a muriatic acid and salt cake furnace will be herein- 25 after more particularly referred to, although it will be understood that the invention is not limited thereto.

In operating a salt cake furnace for production of salt cake and muriatic (or commercial hydrochloric) acid, sulfuric acid and sodium chlorid must be supplied in proper reacting proportions to the furnace; and where a mechanically operated furnace is used, it is necessary that these reagents be 30 fed to the furnace practically continuously and always in substantially the correct relative quantities. To this end it has been proposed to employ an acid feeding device and a salt feeding device, actuated at a 35 constant speed relation by driving means common to both. Proper mechanical feeding of the salt presents no great difficulty; but acid feeders are prone to get out of order and to give trouble, owing to the difficulty of handling highly corrosive liquids 40 by measuring or proportioning devices. For various practical reasons it is desirable to construct such devices of metal, such as cast iron, which, though relatively resistant 45 to concentrated sulfuric acid, is nevertheless subject to more or less corrosion thereby. This is especially so in the case of bearing surfaces exposed to the acid; and hence much trouble has been experienced heretofore from leaky joints caused by corrosion 50 and wear.

Accordingly it is a principal object of the present invention to provide feeding apparatus for sulfuric acid or the like which is positive and accurate in its action, is automatically self-adjusting to compensate for wear caused by corrosion, and which is therefore reliable and durable for comparatively long periods of service.

Under some circumstances, it may be desirable also to vary the feed in accordance with the progress of the process or reaction. That is to say, at certain stages of the process it may be desirable, for example, to greatly increase or diminish the rate of acid feed without affecting the rate of salt feed; or perhaps to entirely supplement the regular acid feed temporarily by other feeding means. It is therefore a further object of the invention to provide feeding means affording such flexibility of operation.

Apparatus for accomplishing the foregoing and other desirable objects in accordance with the invention is hereinafter described and more particularly pointed out in the appended claims.

Typical apparatus within the scope of my invention embodies a rotary feed controlling valve device, of which the movable valve member is constantly urged against its seat to maintain a fluid tight joint at the valve seat by taking up wear due to corrosion and friction; driving means to actuate said valve means; and also, most desirably, supplemental feed means coöoperating with said valve means, for a purpose which will presently appear.

Apparatus embodying the principles of the invention in practical form and adapted more especially for feeding sulfuric acid to a salt cake furnace is shown in the accompanying drawings, in which—

Figure 1 is a view, in elevation, of a complete feeding apparatus, showing the same installed in operative relation to a furnace.

Fig. 2 is a sectional plan view of the feeding apparatus, taken on the line 2—2 of Fig. 1.

Fig. 3 is an end elevation partly in section on the line 3—3 of Fig. 2.

Fig. 4 is a longitudinal sectional view of a portion of the apparatus taken on the line 4—4 of Fig. 2, and

Fig. 5 is a detail view of a portion of means for pressing the feeding valve to its seat.

Referring to the drawings, 10 designates the wall of a muriatic acid and salt cake furnace F which is provided with a pan 11, into which the reacting materials, sulfuric acid and salt, are fed and in which they are mixed by suitable means, not shown.

A suitable pipe 12 leads sulfuric acid through the wall of the furnace 10 and discharges it into the pan 11. Acid is delivered to the pipe 12 from any convenient source of supply, such as an elevated reservoir or tank, shown conventionally at 13, by a novel feeding and controlling system here shown as located between the supply pipe 14, leading from the reservoir, and the discharge pipe 12. In a particularly advantageous arrangement, said system embodies two different conduit paths, by either one or both of which, acid may travel from the supply pipe 14 to the discharge pipe 12. In one of these paths is interposed a rotary valve device driven and controlled by appropriate mechanism, the combination constituting novel acid-feeding means in and of itself. The other path is in the nature of a valve-controlled by-pass intended for temporary alternative use in place of the mechanically actuated feeding means in the other path, or for simultaneous use therewith, as conditions may require. The last mentioned path or by-pass comprises in this instance a pipe 15, provided at 16 with a manually operable cut-off valve, said pipe 15 being connected at its upper end to pipe 14 by a branched coupling 18; while at its lower end it is connected by a branched coupling 19 to pipe 20, which in turn is coupled at 21 to the discharge pipe 12.

The conduit path first mentioned, which is the one normally in use, leads from coupling 18, through nipple 22 and branched coupling 23, down through pipe 24, into valve casing 25, and thence through pipe 26 and coupling 19 into pipe 20. Flow of acid in this path is measured and controlled by the rotatable tapered valve plug 27, which co-operates with tapered valve seat 28 formed inside the valve casing, the parts of the valve device, as well as the piping, being of iron in the present example. The valve plug is of such character that, when rotated, it will feed acid from the upper part of the valve casing into the lower part thereof at a rate accurately controllable by the speed of rotation. In the present example, the plug is formed with two oppositely disposed peripheral pockets or cup-like recesses 29, each of which, during rotation of the valve, receives from above and delivers downward, in more or less rapid succession, measured portions of acid, thus giving an accurately regulable feed which is substantially independent of the hydrostatic head. In order to provide pressure-equalizing or venting means for

the system, the pipe 24 may be extended upward as indicated at 24^a to a point somewhat above the maximum liquid level in tank 13, the upper end of said pipe being open to atmosphere.

The rotary valve device, together with auxiliary operating and controlling parts to be presently described, may be mounted in any convenient manner upon or adjacent the furnace. In the present instance the assemblage is carried by framework consisting of longitudinal channels 30, 31, and cross-pieces 32, 33, said framework being supported, as shown, on the furnace wall.

In the present arrangement the cross-piece 33 is advantageously combined with the valve casing 24, being formed by casting integral laterally extending webbed lugs on opposite sides of the valve casing, such lugs having their outer ends bolted or otherwise suitably secured to the channels 30, 31.

The valve member 27 has a stem 34 which is disposed substantially horizontally and near its outer end it is rotatably supported in a bearing 35 supported on the transverse brace 32. Suitable driving means should be provided cyclically to rotate the valve device. An advantageous and simple arrangement for this purpose comprises a sprocket wheel 36, that is keyed to the valve stem as at 37, and driven from a suitable source of power by a chain 38. The rate of feed may of course be changed as desired by varying the rate of driving.

More or less rapid corrosion of the rotary valve device by the acid is practically unavoidable, so that the valve would soon leak unless means were provided to keep the valve plug firmly held against its seat at all times to compensate for wear. Such compensating means may take various forms, but that here illustrated has important practical advantages. The end of the valve stem which projects beyond the bearing 35 has a collar 39 thereon which is disposed a short distance from the end of the valve stem and provides an abutment shoulder for a thrust ring 40 that fits loosely on the valve stem between the end thereof and the collar 39. The thrust ring 40 has two projections or pins 41 on diametrically opposite sides thereof, which pins project into and loosely work in elongated slots 42 in the upper and lower arms 43 and 44, of a fork or operating lever L, the shank 45 of which may be formed by bending and riveting together one pair of adjacent end portions of said arms. The other ends of the arms are pivoted on the brackets 46 and 47 carried by channel member 31, by means of a bolt 48 which passes vertically through both brackets and both arms and provides a fulcrum for the operating lever. Means should be provided to act on said lever and thereby cause it to exert a thrust on the ring 40 and to press the valve 130

27 axially against its seat at all times. It is desirable to provide means for this purpose which will produce a constant endwise thrust on the stem 34 and valve 27; and to obtain such action I preferably provide a yielding means acting on the free end of the lever. Accordingly, in the construction illustrated, the shank 45 is pivotally connected to a forked spring bolt 49 by a bolt 50, which passes through the shank 45 and the forked portion of the bolt 49. The shank of the bolt 49 is threaded as at 51, to carry a nut 52, which bears against a washer 53. A suitable spring 54 surrounds the bolt 49, and at one end bears against the washer 53, and at its opposite end against a bracket 55, that is riveted or otherwise secured to the channel 30.

The described arrangement of parts operates to draw the free end of lever L to the right, thereby constantly pressing the rotating tapered valve plug against its seat, and causing it to wear itself to a new liquid-tight seat, as fast as the rubbing surfaces 25 are corroded by the acid.

The operation of the system is sufficiently obvious from the foregoing description. Normally the rotary valve feeder is driven continuously at the proper speed to supply acid to the furnace pan or hearth at the required rate, the salt feeder (not shown) being driven at a predetermined speed relation to the acid feeder, as already explained, to insure delivery of both reagents to the furnace in correct relative proportions. If conditions arise which make it necessary to supplement the supply of acid afforded by the rotary valve feeder, the cut-off valve 16 may be opened to permit acid to flow through the by-pass. Or, if required, the rotary acid feeder may be cut out entirely by suitably disconnecting it from the driving means, the valve being so formed as to cut off the flow of acid when 45 not rotating.

While I have shown and described my improved feeding apparatus in detail, it is to be understood that various features thereof may be modified without departing from 50 the scope of the invention.

What I claim is:

1. Feeding apparatus supported upon a fixed frame-work and comprising a conduit having a valve seat therein which is supported from said frame-work, a valve member bearing against said seat and movable to feed predetermined quantities of material through said conduit, means also supported from said frame-work for cyclically moving 55 said valve member, and means constantly pressing said valve to its seat during movement thereof.

2. Feeding apparatus supported within a fixed frame-work and comprising a conduit

having a valve seat therein, a tapering valve 65 plug fitting said seat, which is supported from said frame-work, said valve plug having recesses in its outer surface for feeding predetermined quantities of material through said conduit, means also supported 70 from said frame-work for continuously rotating said valve plug, and means also supported from said frame-work for constantly pressing said valve plug to its seat during 75 rotation thereof.

3. Feeding apparatus comprising a conduit having a valve seat therein, a rotatable valve plug fitting said seat and adapted upon rotation to feed material through said conduit, a stem for said valve plug, driving 80 means connected thereto, and means, including a lever, operatively connected to such valve stem but permitting rotation thereof and arranged to press said valve to its seat.

4. Feeding apparatus comprising a conduit having a valve seat therein, a rotatable valve plug fitting said seat and so formed that upon rotation it will feed material through said conduit, a stem fast with said valve plug, a bearing for said stem, a driving member on said stem, and means, including a resiliently actuated lever, operatively connected to said stem and arranged to exert a longitudinal thrust thereon, thereby to yieldingly press said valve plug to its 95 seat while permitting rotation thereof.

5. Feeding apparatus comprising a supporting frame work, a valve casing mounted thereon and provided with a valve seat, a feeding valve member movable on said seat 100 and provided with a stem, a bearing for said stem carried by said framework, driving means connected to said stem and arranged to impart feeding movement to said valve member, and means also connected to said stem and operative to press said valve member against its seat.

6. Feeding apparatus comprising a supporting framework, a valve casing mounted thereon and provided with a tapering valve 110 seat, a rotatable tapered valve plug engaging said seat, said plug being peripherally cupped or recessed, a stem fast with said plug and supported by said framework for both rotational and longitudinal movement, a rotational driving member carried by said stem, a lever pivoted on said framework and operable to exert a valve-seating thrust on the valve stem, and resilient means acting on 115 said lever to maintain such thrust.

7. Acid feeding apparatus comprising the combination, with a source of acid supply and a discharge pipe arranged at a lower level, of acid feeding means interposed at an intermediate level between said source of 125 supply and said discharge pipe and comprising a conduit, a rotary feeding valve member seated in said conduit, means for

continuously rotating said valve member, and means for constantly pressing it against its seat without interfering with rotation.

8. The combination with a source of supply, and means for utilizing material from said source, of means for feeding material from said source to such utilizing means at a predeterminable rate, and means for feeding material to such utilizing means independently of the first mentioned feeding means.

9. The combination with a furnace and

means containing a supply of a chemical, of means for feeding said chemical to said furnace comprising a pipe and means in said pipe for feeding such chemical, and a valved by-pass through which chemical may be fed to said furnace in addition to or independently of the first mentioned feeding means.

In testimony whereof I hereunto affix my signature.

LEWIS BAILEY SKINNER.
